ARTHUR H. MAYNARD, OF WARWICK, RHODE ISLAND, ASSIGNOR TO BOSTON WIRE STITCHER COMPANY, OF AUGUSTA, MAINE, A CORPORATION OF MAINE.

DIFFERENTIAL MOTION FOR WIRE-STITCHERS OR LIKE MACHINES.

1,255,201.

Specification of Letters Patent.

Patented Feb. 5, 1918.

Application filed May 26, 1916. Serial No. 100,022.

To all whom it may concern:

Be it known that I, ARTHUR H. MAYNARD, a citizen of the United States, residing at Warwick, in the county of Kent, State of Rhode Island, have invented certain new and useful Improvements in Differential Motions for Wire-Stitchers or like Machines, of which the following is a specification.

My invention relates to wire-stitching or stapling machines for forming staples and inserting them through overlapping thicknesses of paper, cardboard or other material to fasten their parts together. The invention consists particularly of an improved differential motion for operating the bender-bar, which forms the staple from lengths of wire fed thereto, and the coöordinated mechanism for driving the staples through the work and clenching their legs thereagainst. The objects of the improvement are to simplify the operating-mechanism of the machine; to increase its durability; and to render the coöperation of the bender-bar and staple-driver more efficient for the purpose intended and also adaptable to a wider range of work.

The manner and means for carrying out these improvements are fully described in the following specification, illustrated by the accompanying drawings, in which like reference characters designate like parts. In the drawings: —

Figure 1 is a side view in vertical section of a stitcher-head illustrating the essential elements of the staple-forming and driving mechanisms and showing their connection with the operating-means therefor;

Fig. 2, a front elevation of the operating-means for the reciprocating bender-bar and staple-driver, showing these latter elements approaching the end of their upward stroke;

Fig. 3, a similar view showing the bender-bar at the start of its downward stroke and the driver in position just previous to the beginning of its stroke downward;

Fig. 4, a similar view illustrating the bender-bar at the end of its downward stroke with the driver approaching this end of its movement; and

Fig. 5, a similar view showing both the bender-bar and driver in lowermost position in the act of completing the clenching of the 55 staple in place.

Referring first to Fig. 1, my improved mechanism is here shown as applied to a vertical type of stitcher-head such, for instance, as that described in U. S. Patent 60 No. 970,461, granted Sept. 20, 1910, to T. A. Briggs. It is to be understood, however, that my improvements are adapted for use with other forms of stitcher-mechanism and might also be employed in connection with 65 other machines of a similar nature. In Fig. 1 the stitcher-head is shown in section to illustrate the operating-mechanism inclosed in the bonnet B which forms a part of, or is attached to the front of, a horizontal arm 70 A. The arm A extends forwardly from the main standard or frame of the machine, not here illustrated, and overhangs a horizontal table or work-support T on which the material to be stitched is placed to bring it 75 into position beneath the bonnet B. The work-support T carries a clencher-block t, at its outer end which coöperates with the stitcher-mechanism in the bonnet B to clench the legs of the staple in place, see 80 Fig. 5, or in some instances movable clenchers are employed in its stead. Extending through the arm A and rotatably mounted in suitable bearings, only one of which is here shown at b, is the main drive-shaft S 85 for operating the stitching-mechanism in the bonnet B. The shaft S is connected to the source of power at its rearward end by a suitable belt-pulley, or the equivalent, and is usually controlled by a clutch-device, 90 but these elements form no part of the present invention and they are not herein shown or described.

Fastened to the front of the head or bonnet B are two opposite, side-members or 95 vertical guide-rails G, only one being shown in Fig. 1, on which the reciprocating parts of the mechanism slide. These latter consist essentially of a driving-bar D; a driver-bar D' connected to be reciprocated therewith; a staple-driver D² carried at the lower end of the driver-bar D'; and the staple-former or bender-bar C arranged to be reciprocated independently of the other slid-

ing parts. The driving-bar D consists of a rectangular plate having splines d on its opposite sides fitted to slide in vertical grooves g in the sides of the guide-rails G. The bender-bar C is likewise of rectangular, plate-like construction, having splines c on its sides, see Figs. 2 to 5, also fitted to the guiding-grooves g . On its front the bender-bar C is formed with a vertical slot c' providing two opposite, parallel sides c^2 , c^2 connected at the rear by a web c^3 , see Fig. 1. The opposite sides c^2 , c^2 of the bender-bar C project downwardly beyond the lower end of their connecting-web c^3 to form the parallel legs c^4 , c^4 which coöperate with a forming-anvil F, illustrated only in Fig. 1, to bend the legs of the staple at right-angles to its top. Mounted to slide in the central slot c' of the bender-bar C is the driver-bar D', which is of substantially plate-like construction with its sides fitting between the sides c^2 , c^2 while its upper end projects above the top of the bender-bar. At its upper end the driver-bar D' has a tongue-and-groove connection at d' with the lower end of the driving-bar D to adapt the two members to operate together as one part. The staple-driver D² consists simply of a relatively thin plate let into the front face of the driver-bar D and fastened in place in any suitable manner to provide for its removal for repair or replacement. The sides of the driver D² are formed with splines d^2 , d^2 fitted to slide in grooves c^5 , c^5 in the sides c^2 , c^2 of the bender-bar C to retain the driver-bar in place in the slot c' . The lower edge of the driver D² is adapted to make contact with the top of the staple x , see Fig. 5, to drive its legs through the work X and clench them in place against the under side thereof, as more fully explained hereinafter.

The forming-anvil F is rotatably supported in a sleeve-like bearing f mounted on one side of the bonnet B, and is adapted to slide longitudinally of its axis. Its inner, beveled end is recessed with a slot f' adapted to receive the wire fed down from the top of the machine and severed into lengths for the staples, the means for these last-named operations not being herein described or illustrated as they may be of any usual construction as well known in the art. After a length of wire has been cut off from the main strip it is grasped by the anvil F and turned into horizontal position beneath the staple-former C. As the former C descends its sides or legs c^4 , c^4 straddle the sides of the anvil F and, acting on the ends of the length of wire projecting therefrom, bend them down at right-angles to the central portion of the wire held in the slot f' to form the opposite, parallel legs of the staple. After the staple has thus been

formed the driver D² descends against its top and as the lower edge of the driver comes into engagement with the forward, beveled end of the anvil F it slides the latter back out of the way. The arrangement and method of coöperation of these last-named parts are explained in detail in the patent to Briggs before referred to and will not, therefore, be herein further described. Pivotally mounted on the rear of the bender-bar C is a staple-supporter H arranged to adapt its lower end to swing into position between the legs c^4 , c^4 to hold the staple in place while it is being driven through the work. This device is similar in function to other arrangements commonly in use, and as it has no relation to the present invention it will not be herein described in detail.

As before explained the driving-bar D with its connected parts and the bender-bar C are arranged to slide up and down on the guide-rails G, and the means for reciprocating them with a differential motion, to effect their synchronous operation in forming and driving the staple, constitute the essential features of my improvement. Referring particularly to Fig. 1, the drive-shaft S carries a crank-disk J keyed to its outer end at j , to rotate therewith, and serving as the prime-mover for all of the several reciprocating parts hereinbefore referred to. On the outer face of the disk J is an eccentric hub K secured thereto by two pins k , k' , see Fig. 2, riveted through the disk as shown in Fig. 1. One of the pins k is formed with a collar or flange k^2 abutting the front face of the hub K and an enlarged head or extension k^3 projecting outwardly therefrom. The head k^3 serves as a crank-pin for a connecting-rod L pivotally journaled thereon and having its opposite, lower end pivoted on a wrist-pin m. The wrist-pin m is riveted or otherwise fastened to the driving-bar D, as shown most clearly in Fig. 1, and in this manner the bar D and the parts carried thereby are connected to the crank-disk J to be reciprocated therefrom with a stroke equal to the throw of the crank-pin k . As illustrated in Fig. 1, the connecting-rod L is provided with an oil-hole l at its upper end which leads to an oil-groove l' , scored on the periphery of the crank-pin k , and thence communicates with a duct l^2 for conducting the lubricant down to the wrist-pin m.

The bender-bar C is also connected by a pitman N to be reciprocated from the crank-disk J, but with a different timing of its movement and with a variable length of stroke as next described. The pitman N is constructed for longitudinal expansion and contraction and comprises two telescoping members N' and O. The upper member N' is formed with a strap-like bearing n sur-

rounding the eccentric hub K on the disk J, to adapt it to turn thereon, and bored with an oil-chamber or pocket n' . Extending downwardly from the eccentric-strap n is an 5 arm n^2 bored longitudinally at n^3 to receive the rod O which forms the sliding extension of the pitman N. The rod O is inserted through the oil-hole n' in the member N' and is formed with a head o which seats 10 against the bottom of the hole to limit its sliding movement in the bore n^3 . The lower end of the rod O is screwed into a T-shaped bearing-member O' and held in place by a set-screw o'. The bearing-member O' is 15 formed with a cross-bore o^2 in which is journaled a wrist-pin P riveted or otherwise secured to the rear of the bender-bar C. The upper arm of the member O' is reduced in diameter at o^3 to receive the end of a coiled 20 spring R which bears against an annular shoulder o^4 . The upper portion of the spring R surrounds the arm n^2 of the member N' with its end bearing against a shoulder n^4 . The tendency of the spring R will be to 25 maintain the parts of the pitman N extended to the full length as illustrated in Fig. 1, with the head o of the rod O seated against the bottom of the bore n' . The spring R may be compressed, however, to allow the 30 rod O to slide within the member N' to reduce the length of the pitman, and thereby the distance between the axes of the crank-pin k and wrist-pin m. In this manner the 35 length of stroke of the bender-bar C is made variable in accordance with the thickness of the stock being operated upon and, furthermore, the bender-bar is forced against the work with a yielding pressure in the manner and for the purpose as fully described 40 hereinafter. The object of this arrangement of the mechanism is to adapt the bender-bar to act against the work with a yielding pressure and to effect a dwell at the end of its stroke, similar to the well-known method of 45 operation of the presser-foot on a sewing machine. The method of operation of the complete mechanism is as follows:

The drive-shaft S is rotated continuously throughout the operation of the machine and 50 the crank-pin k³ on the disk J acts through the connecting-rod L to reciprocate the driving-bar D with a constant extent of stroke. Referring to Figs. 2 to 5, the crank-disk J rotates in the direction indicated by the 55 arrow 2, and the arrangement of the crank-pin k³ with respect to the axis of the eccentric hub K is such that the connecting-rod L will follow the pitman N both in its downward and upward strokes. Referring to Fig. 60 3, it will be observed that the pitman N, connected to the eccentric hub K, will commence its downward stroke immediately the center of the hub K passes across the vertical plane of the axis of the crank-disk J;

while the connecting-rod L will not start to 65 descend for an interval thereafter, or until the center of its crank-pin k³ has passed the same point. In this way the bender-bar C is caused to first move downwardly to bring its lower end into coöperation with the forming-anvil to bend down the legs of the staple, as before explained, and meanwhile the driver-bar D follows the bender-bar in its downward stroke, but with a differential movement therebetween. Fig. 4 illustrates 70 the parts in their relative positions at the instant that the lower ends of the bender-bar legs c⁴, c⁴ come into contact with the work X being stapled, which, as before explained, is supported on the work-table T. As the 75 bender-bar C is brought down against the work X, its further movement will be resisted thereby but the driver-bar D will still continue to move downward, causing the driving-bar D' and its attached staple-driver 80 D to slide in the slot c' of the bender-bar. Meanwhile, the formed staple x is held by the staple-supporter H shown in Fig. 1, with its legs engaging the shallow grooves c⁵, c⁵ in the legs c⁴, c⁴ of the bender-bar C as illustrated in Fig. 4. Now, as the driver D continues to slide downward in the bender-bar C, its lower edge bearing against the top of the staple x will force the latter down and drive its legs through the stock X. As the 85 legs of the staple protrude through the under side of the work X they come into contact with the clencher-block t, see Fig. 5, and are thereby bent over and clenched against the material in the usual manner. 90

Referring to Figs. 4 and 5, it is to be noted that during this last-described movement of the driver D to drive and clamp the staple x in place, the bender-bar C remains at rest. This pause or dwell of the 100 bender-bar at the bottom of its stroke is provided for by the compression of its spring-extended pitman N in the following manner: As shown in Fig. 4 the bender-bar C reaches the lower limit of its movement, as 105 defined by the thickness of the work X, before the eccentric hub K reaches the lowermost end of its stroke. In other words, the bottom of the bender-bar C comes into contact with the work X before the axis of the hub K, indicated at 3 in Fig. 4, has reached the vertical plane of the axis of the crank-disk J, represented by the dot-and-dash lines 4—4. Hence, as the axis of the hub K passes from the point 3, illustrated in Fig. 110 4, to point 5 as shown in Fig. 5, the pitman N will be required to yield, its parts O and N' telescoping and contracting the spring R. After the clenching of the staple has been completed the driver D starts to ascend as 115 its crank-pin passes across the vertical plane 4—4 of its axis of rotation. At this instant the center of the eccentric hub K will have 120 125

reached the position 5 as shown in Fig. 5 and the bender-bar C will start to rise with the driver D. It will be noted from the dot-and-dash lines 6—6 and 7—7 in Fig. 2, that 5 the radial distance of the center of the crank-pin k from the axis of the disk J is greater than that of the center of the hub K and hence the parts operated from the connecting-rod L will have a longer stroke 10 and a faster movement than that of the bender-bar C operated from the pitman N. This results in the driver D being raised more quickly than the bender-bar C to cause it to slide upwardly therein so that it will 15 be out of the way when the bender-bar starts its descent again to form the next staple. In other words, the bender-bar C and driver D are operated with a differential motion which causes the bender-bar to descend first 20 to form the staple and the driver to follow it to insert the staple in place, after which the driver is quickly retracted with respect to the bender-bar to allow the parts to act again as first described, the reciprocal movements of the parts being synchronously continued in successive cycles. In this manner 25 the bender-bar C is maintained in contact with the work X during the interval while the staple is being driven therethrough 30 and clenched in place. Through this provision the work is held in position against accidental displacement so that the staple will be applied in proper relation to the seam being stitched.

35 Another object of this improved method of action of the bender-bar is to adapt the stitching-mechanism to operate on different thicknesses of stock without requiring adjustment in the length of its stroke. For instance, if the thickness of the stock should 40 vary slightly, or if more than the prescribed thicknesses required to be stitched should be placed in the machine, inadvertently or through accident, the bender-bar will automatically accommodate itself to such variations, within certain limits, through the arrangement of its self-conforming pitman N. In this manner I provide for a yielding action of the bender-bar on the work, with its 45 pressure controlled resiliently instead of positively, and with its operation timed to effect a dwell to hold the work in place while the material is being stitched.

It will be observed from the above that 55 my improvement provides an extremely simple mechanism for operating the stitching-devices to secure the results desired and one which is particularly staunch and rugged, capable of resisting severe stresses 60 and proof against deterioration or damage in use. Furthermore, my improved device is adapted to a wider range of work without adjustment than similar mechanisms previously employed for the same purpose, and is

self-conforming to allow for irregularities 65 in the thickness of the stock.

Various modifications might be made in the construction and arrangement of the parts of the mechanism and the manner of applying it to different types of apparatus 70 without departing from the spirit or scope of the invention; therefore, without limiting myself to the exact embodiment shown, what I claim is:—

1. In a differential-motion for wire-stitching machines or other apparatus, the combination with a rotating crank-disk, of an eccentric hub on said disk, a longitudinally contractible pitman journaled on said hub to be reciprocated therefrom, a crank-pin 80 arranged eccentric to the center of the hub, and a connecting-rod journaled on the crank-pin to be reciprocated with a differential movement with respect to the pitman.

2. In a mechanism of the class described, 85 the combination with a rotating crank-shaft, of an eccentric hub revolving about the axis of the shaft, a crank-pin revolving therewith with a greater length of throw, a connecting-rod journaled on the crank-pin to 90 be reciprocated therefrom, and a longitudinally contractible pitman journaled on the eccentric hub to be reciprocated therefrom and adapted to be contracted to equalize the operative effect of its stroke with the 95 stroke of the connecting-rod.

3. In a mechanism of the class described, 100 the combination with a rotating crank-shaft, of a connecting-rod adapted to be reciprocated therefrom, a pitman also connected with the crank-shaft to be reciprocated with a differential motion with respect to the connecting-rod, said pitman being longitudinally contractible to equalize the operative 105 effect of its stroke with that of the connecting-rod.

4. In a mechanism of the class described, 110 the combination with a rotating crank-shaft, of a connecting-rod reciprocated from said crank-shaft, and a resiliently-extended pitman connected to be reciprocated from the crank-shaft with a differential motion with respect to the connecting-rod but adapted to contract longitudinally under pressure to equalize the operative effect of its stroke 115 with that of the connecting-rod.

5. In a mechanism of the class described, 120 the combination with a rotating crank-shaft, of a connecting-rod reciprocated from said crank-shaft, a longitudinally contractible pitman also connected to be reciprocated from the crank-shaft, a member connected with the pitman to be reciprocated thereby, and a second member arranged to slide in the first member and adapted to be reciprocated with a differential motion in relation thereto through its connection with 125 the connecting-rod.

6. In a mechanism of the class described, the combination with a rotating crank, of a connecting-rod reciprocated therefrom, a revolving eccentric hub, a longitudinally contractible pitman connected to be reciprocated thereby, a sliding member connected to be reciprocated by the pitman, and a second member slidable in the first member and connected to be reciprocated from the connecting-rod with a longer stroke and faster motion than that of the first member. 65
7. In a wire-stitching or stapling machine, the combination with a rotating crank-shaft, of a resiliently-extended longitudinally-contractible pitman connected to be reciprocated therefrom, a bender-bar connected to be operated from the pitman to form the staples from lengths of wire fed thereto, a connecting-rod also reciprocated from the crank-shaft with a longer stroke than that of the pitman, and a staple-driver connected to be reciprocated from the connecting-rod with a differential motion with respect to the bender-bar. 70
8. In a wire-stitching or stapling machine, the combination with a reciprocable bender-bar for forming staples from lengths of wire fed thereto, of a reciprocable driver for driving the formed staples through the work, a crank-shaft, a spring-extended longitudinally-contractible pitman connected to the crank-shaft to reciprocate the bender-bar, and a connecting-rod also connected to the crank-shaft to reciprocate the driver with a faster rate of movement than that of the bender-bar. 75
9. In a wire-stitching or stapling machine, the combination with a reciprocable bender-bar for forming staples from lengths of wire fed thereto, of a driver coöperating therewith for driving the formed staples through the work, a rotating crank-disk, an eccentric hub on said disk, a pitman journaled on said hub and connected to reciprocate the bender-bar therefrom, a crank-pin on the crank-disk arranged eccentric to the center of the hub, and a connecting-rod journaled on the crank-pin and connected to the driver to reciprocate the latter with a differential motion in relation to the bender-bar. 80
10. In a wire-stitching or stapling machine, the combination with a reciprocable bender-bar for forming staples from wire fed thereto, of a reciprocable driver for driving the staples through the work, a longitudinally-contractible pitman for reciprocating the bender-bar, and means for reciprocating the driver with a constant length of stroke, the stroke of the bender-bar being variable through the contraction of its pitman. 85
11. In a wire-stitching or stapling machine, the combination with a reciprocable bender-bar for forming staples from wire fed thereto, of a reciprocable driver coöperating therewith for driving the staples through the work, means to reciprocate the driver, means to reciprocate the bender-bar, and a resilient telescoping connection between the bender-bar and its reciprocating means, whereby said bender-bar is held against the work with a yieldable pressure during the operation of setting the staple in place. 90
12. In a wire-stitching or stapling machine, the combination with a reciprocable bender-bar for forming the staples and guiding them into position against the work, of a reciprocating driver coöperating with the bender-bar for driving the staples through the work, and a resiliently-extended longitudinally-contractible connection for reciprocating the bender-bar to force it against the work with a yieldable pressure while the staple is being driven therethrough. 95
13. In a wire-stitching or stapling machine, the combination with a reciprocable bender-bar for forming the staples and guiding them into position against the work, of a reciprocating driver coöperating with the bender-bar to insert the staples through the work, and a resiliently-extended pitman for operating the bender-bar to force it against the work with a yielding pressure while the staple is being set therein. 100
14. In a wire-stitching or stapling machine, the combination with means for holding the lengths of wire fed thereto to be formed into staples, of a reciprocable bender-bar for coöperating with said means to bend down the legs of the staple, and a longitudinally contractible pitman for reciprocating the bender-bar to adapt it to act against the work being stapled with a yielding pressure. 105
15. In a wire-stitching or stapling machine, the combination with a relatively stationary anvil for holding lengths of wire fed thereto to be formed into staples, of a reciprocable bender-bar for coöperating with the anvil to bend down the legs of the staple, means to reciprocate the bender-bar, and a longitudinally contractible connection between the reciprocating-means and the bender-bar to adapt the latter to act with a variable stroke and a yielding pressure against the work being operated upon. 110
16. In a wire-stitching or stapling machine, the combination with a reciprocable bender-bar for forming staples from lengths of wire fed thereto, of a contractible pitman for reciprocating said bender-bar, said pitman comprising an eccentric-strap having a depending arm formed with a longitudinal bore, a rod slidable within said bore and carrying a bearing for a wrist-pin at its end, and a coiled spring surrounding the arm and rod and acting against the end. 115

bearing of the latter to normally maintain the parts in extended relation.

17. A longitudinally-contractable pitman for wire-stitchers or like machines comprising a member formed with an eccentric strap and an arm extending therefrom, said arm having a longitudinal bore communicating with a larger bore extending axially therefrom, a rod slidable in the smaller bore

and formed with a head seated against the bottom of the larger bore, a T-headed bearing secured to the outer end of the rod, and a coiled spring surrounding the arm and the rod and acting against the T-headed member to maintain the parts in extended relation. 15

In testimony whereof I affix my signature.
ARTHUR H. MAYNARD.
